UNITED STATES PATENT OFFICE.

GEORGE W. FERGUSON, OF MINNEAPOLIS, MINNESOTA.

TOY.

Application filed March 16, 1921. Serial No. 452,801.

My invention relates to toys and particularly to the type of toy mounted on wheels and has for its object to provide a jointed figure mounted on a plurality of wheels adapted to go through grotesque motions as the wheels are rotated, with means for limiting the movement of the jointed members of the figure when the toy moves into its different positions.

10 Another object of the invention is to provide means for movements of guiding and arresting certain portions of the toy so as to cause the toy to have movements characteristic to the object represented by the toy.

15 A still further object of the invention is to provide adjusting means for the relative positions of the supports for the toy and the arresting means so as to vary the motions of the toy when in operation.

20 In carrying out my invention I provide a toy in the shape of an animate object which may have its limbs connected to crank arms attached to the wheels on which the toy is mounted. In conjunction with this I provide stops on the toy which engage portions of the limbs to terminate their motion in a particular direction and to cause the limbs to move in the opposite direction relative to the toy. I further provide a frame member for journaling the wheels which is adjustable in length and which is adapted to vary the distance between the supports on the toy to give the results desired.

25 The full objects and advantages of my invention will appear in connection with the detailed description thereof and are particularly pointed out in the claims.

In the drawings, illustrating the application of my invention:

30 Fig. 1 is a perspective view of one form of the invention.

Fig. 2 is a perspective view of the form of the invention, indicated in Figure 1 showing the toy in one of its extreme positions.

45 Fig. 3 is a view similar to Figure 2 showing the toy in another of its extreme positions.

Fig. 4 is a plan view of a portion of the invention shown in Figure 1.

50 Fig. 5 is a view similar to Figure 1 of another form of the invention.

Fig. 6 is a view similar to Figure 3 of the form of the invention shown in Figure 5.

Fig. 7 is a perspective view of still an-

other form of the invention similar to that shown in Figures 5 and 6.

Fig. 8 is a plan view of a portion of the invention shown in Figure 7.

Fig. 9 is a rear elevational view of a portion of the invention shown in Figure 2.

In the form of the invention shown in Figures 1, 2, and 3, I provide four wheels, 10, 11, 12, and 13 which have fastened to them axles 14 and 15 mounted at the geometrical centers of said wheels. These axles are provided with crank portions 16 and 17 which extend substantially the entire length of the axel. A frame comprising four rods 19, 20, 21 and 22 is journalled on portions 18 of axels 14 and 15 adjacent wheels 10, 11, 12 and 13 by means of journals 23 formed on the ends of said rods by bending said rods in the shape of an eye. Rods 19, 20, 21 and 22 extend through a bar 24 positioned transversely of the frame and are slidably mounted in said bar and kept from moving in the same by the friction of the bar on said rods. By sliding these rods in the bar an adjustment of the length of the frame can be obtained so that the relative positioning of the parts of the toy can be altered to suit the requirements as will be later explained.

The toy proper comprises a figure 25 in the shape of a body of a donkey which has pivoted to it at 26 and 27 four legs 28, 29, 30 and 31. These legs are beveled at their pivoted ends where they engage the body of the figure 25 so that said legs spread towards the hoofs of the animal when the pivots 26 and 27 are in place. Legs 28, 29, 30 and 31 are rotatably mounted upon the cranks 16 and 17 which extend through said legs at the hoofs of the animal. Upon the back of the donkey is mounted the figure of a man having a body portion 32 and a head 33 formed integral therewith, jointed arm members 34 and 35 and jointed leg members 36 and 37 pivoted thereto. Arm members 34 are pivoted to the donkey at 38 at the hands of the man and leg members 37 are pivoted to the donkey at 39 through the heels of the leg. All of the joints in both the man and the donkey including pivots 27 and 26 are made loose so that the donkey is free to move upon the crank members 16 and 17 and both the donkey and the man are adapted to move freely in all of their joints.

With the exception of a device to be pres-

ently explained, the donkey has no other support on the frame and wheels of the toy than through its legs and the crank members 16 and 17. The device is adapted to 5 be drawn about on the floor by means of a string 40 tied to a looped draw bar 41 formed integral with the rods 19 and 22. As the toy is drawn about on the floor, wheels 10, 11, 12 and 13 are caused to rotate, revolving within them the cranks 16 and 17. As these cranks turn, legs 28, 29, 30 and 31 10 of the donkey are caused to travel with them, which legs impart to the donkey great variety of motions.

15 To limit the relative movement of the legs of the donkey in regard to the body I provide pairs of stops 42 and 43 secured to the body of the animal in the proximity of the pivots 26 and 27 which are adapted 20 to engage pins 44 provided on the ends of each of the leg members 28, 29, 30 and 31. These stops and pins serve a duplicate purpose, first in limiting the movement of the legs on the donkey to prevent the donkey 25 from collapsing or completely falling down, and secondly, in imparting to the body of the donkey a motion in the opposite direction when one of the pins 44 hits either of the stops 42 and 43. In this way the donkey is given a very simple motion. As the 30 toy is drawn along the floor and the legs of the donkey moved on cranks 16 and 17 the donkey is thrown in positions varying between that shown in Figure 2 to that 35 shown in Figure 3, the said pin 44 and stops 42 and 43 terminating this movement.

By observing the drawings it can be noticed that the two pairs of wheels travel independently of each other so that the two 40 cranks 16 and 17 may be traveling at the same distance from each other or may have their crank arms disposed in relatively different angles to one another. In the event that the two crank arms travel the same 45 distance apart throughout their rotation, both sets of legs simultaneously are moved successfully forward, downward, rearward and upward which gives the donkey and rider a galloping or jumping appearance.

50 As the toy is drawn along, through irregularities in contact of the wheels on the floor and due to irregular slippage of the same the relative positioning of the cranks varies. As soon as one of the cranks is in advance 55 of the other the legs are independently given their four motions which cause the donkey to have a bucking or kicking movement. When the cranks are operating exactly 180 degrees apart the donkey moves substantially straight up and down while his legs travel simultaneously together and away from each other so that the donkey has the appearance of galloping at a high rate of speed. Slight variations in the relative angular positions of the crank arms 16 and 17

with one another produce several variations in the movements of both of donkey and the man as the toy is operated. The man being loosely jointed by being pivoted to the donkey at the two points 38 and 39 is able to 50 raise up from the back of the donkey and to descend again on the donkey's back as the body of the donkey is put through its various motions by the cranks. Two such motions are shown in Figures 2 and 3 when 55 the donkey is at two of its extreme positions. Numerous other positions can also be taken by the man which give him a very animated appearance.

To further vary the movements of the 60 toy I provide a U-shaped upright 45 which is slidably mounted in the bar 24 and which is adapted to engage the under portion of the body 10 of the donkey anywhere along its surface at 46 between the legs 28, 29, 30 65 and 31. This upright quickly arrests the downward motions of the donkey in either its forward or rearward reciprocation which gives the donkey a movement similar to that of a lunge or a sharp kick. The same device 70 also causes the body of the donkey to oscillate on the point of contact of said upright as a pivot, which, due to the momentum of the body tends to rotate either of the cranks 16 or 17 relative to each other in 75 opposition to the friction of the wheels of the toy on the floor so that the relative positioning of the cranks 16 and 17 is constantly being changed without effort on the part 80 of the person operating the toy. It can hence be seen that the toy continuously passes through varying grotesque motions which are constantly being changed as the 85 toy is operated.

As before stated the rods or frame members 19, 20, 21 and 22 are slidably mounted in the bar 24. When the frame is extended by pulling these rods outwardly the donkey has shorter movements with the possibility of one of the sets of legs remaining 90 stationary relative to the body while the other pair is engaged in oscillating movement relative to the same. By adjusting the upright 45 in the bar 24 the motions of the 95 toy can be still further changed.

In the form of the invention shown in Figures 5 and 6, I provide a pair of wheels 47, 48, 49 and 50, fixed to axels 51 and 52 which have crank portions 53 and 54 similar to the device shown in Figure 4. These 100 axels are journaled in a frame member 53 formed of a single piece of wire bent with eyes at 54 for journaling said axels 51 and 52 and extending in the form of a loop, in 105 advance of the toy to serve as a draw bar to which a string 55 may be attached by means of which to draw the toy. The figure in this case is that of a person having a body 56 and legs 57 and 58 pivoted to said 110 body at 59 and arms 60 and 61 pivoted to 115

said body at 62. Arms 60 and 61 are free to move relative to the body as the same is put through various motions while the legs 57 and 58 are each respectively pivoted to the cranks 53 and 54 in the form of the legs 57 and 58 and similarly formed with pins 63 fastened to the body 56.

The operation of this device is similar to that shown in Figures 2 and 3. As the toy 10 is drawn about on the floor by means of

string 55 the cranks 53 and 54 impart to legs 57 and 58 motions in conjunction with the stops 64 and 65 and the pin 63 which give the entire figure movements similar 15 to that of a person running and jumping.

Whenever cranks 53 and 54 change relative angular position the movements of this toy vary accordingly. When both cranks travel parallel the toy has a leaping motion, the 20 body moving principally up and down. As the cranks vary in angular position relative to each other the figure gets an oscillating motion back and forth in combination with the alternate raising and lowering of the 25 legs, the arms 60 and 61 swinging freely as the toy travels along the floor. It can be clearly seen that the motions through which the toy can be put are quite animated, and that the variety of gestures and postures are very numerous.

In Figures 7 and 8 I have shown a combination of two such toys as shown in Figures 5 and 6 mounted on a single frame 66, which frame carries three sets of wheels 35 and axles 67, 68 and 69. I here show two figures 70 and 71 mounted on the axles 72, 73 and 74 of this device which figures are placed facing each other as shown in Figure 7 and which have two of their legs 75 and 40 76 pivoted to the middle axle 73. As this toy is drawn about on the floor each of the figures 70 and 71 pass through the same gestures and motions as that shown in Figures 5 and 6. The movement of these figures 45 towards each other and the free swinging of the arms of figures towards each other give the figures the appearance of a couple of prize fighters. In addition to the reverse movements of the figures caused 50 by the pins 63 and stop 64 and 65 the figures are quickly thrust away from each other when they directly engage each other either through their heads or the arms of the same, thus adding other movements to said figures 55 not present with the toy shown in Figures 5 and 6.

The advantages of my invention are manifest. A toy is provided which is capable of passing through a most varied 60 course of movements, which movements are constantly changing as the toy is being operated. The toy may be made to resemble animated objects and the movements are such as are clearly characteristic of the object represented. The toy can be made very

cheaply and is of such a simple construction that it will not easily get out of order, thus rendering the same substantial and serviceable. My toy is designed especially to appear to the eye and is of such an appearance that even when stationary the same is highly attractive. The toy is always passing through some new motion or 70 antic to the great amusement of the operator.

In accordance with the patent statutes I have described the principles of operation of my invention, together with the apparatus which I now consider to represent the best embodiment thereof, but I desire to 75 have it understood that the construction shown is only illustrative and that the invention can be carried out by other means and applied to uses other than those above set forth within the scope of the following 80 claims.

I claim:

1. A toy comprising a frame member, a pair of axles journaled in said frame member, cranks formed on said axles, a plurality of wheels secured to said axles, a figure in the shape of an animal having a body and a plurality of legs pivoted thereto, said legs being pivoted to the axle for freely supporting said animal thereon independently of the frame, and means co-operating between the legs and body independent of the frame for holding the figure upright.

2. A toy comprising a frame member, a pair of axles journaled in said frame member, cranks formed on said axles, a plurality of wheels secured to said axles, a figure in the shape of an animal having a body, a plurality of legs pivoted thereto, said legs being pivoted to the axle for freely supporting said animal thereon independently of the frame, and means associated with said legs and body for holding the animal in an upright position.

3. A toy comprising a frame member, a pair of axles journaled in said frame member, cranks formed on said axles a plurality of wheels secured to said axles, a figure in the shape of an animal having a body, a plurality of legs pivoted thereto, said legs being pivoted to the axle for freely supporting said animal thereon independently of the frame, and means for confining the movement and of momentarily arresting said animal in its movements to alter the direction of travel of the same.

4. A toy comprising a frame member, a pair of axles journaled in said frame member, cranks formed on said axles, a plurality of wheels secured to said axles, a figure in the shape of an animal having a body portion, a plurality of legs pivoted thereto, said legs being pivoted to the cranks of said axles, a projection formed on each of said legs

and stops formed on said body portion adapted to be engaged by the projection on said legs to assist in holding the figure upright and to alter the direction of movement of the same.

5. A toy comprising a frame member, wheels journaled in said frame member, a figure having a body portion, legs pivoted to said body portion, said legs being eccentrically connected with said wheels, pairs of stops on said body adjacent each of said legs and means on said legs adapted to be engaged by said stops to hold the figure upright and to vary the motion of said figure.

10. A toy comprising a pair of wheels, axels secured to said wheels having cranks formed thereon, a frame journaled on said axels, a figure representing an animated object having a body portion, legs pivoted at one end to said body portion and to the axels at their other end, said body portion being placed above the frame, a member supported on said frame adapted to engage the underside of the body portion to change the direction of movement of said body portion imparted to it by said cranks, and means for adjustably holding said member attached to said frame.

15. A toy comprising pairs of wheels, axels connected to said wheels, a front frame member journaled on one of said axels and a rear frame member journaled on the other of said axels, and means for slidably holding said frame members in adjustable position relative to each other.

20. A toy comprising pairs of wheels, axels connected to said wheels and having cranks formed on said axels, a front frame member journaled on the other of said axels, means for slidably holding said frame members relative to each other, a draw bar formed on the front frame member, a figure representing an animated object having a body portion, a plurality of legs pivoted to said body portion at one end and to said cranks at their other end, said body being positioned above said frame members.

25. A toy comprising pairs of wheels, axels connected to said wheels and having cranks formed on said axels, a front frame member journaled on one of said axels, a rear frame member journaled on the other of said

axels, and means for slidably holding said frame members in relative positions, a draw bar formed on the front frame member, a figure representing an animated object having a body portion, a plurality of legs pivoted to said body portion at one end and to said cranks at their other end, said body being positioned above said frame members, and means engaging a portion of the body for changing the direction of the motion imparted to the body through said cranks.

30. A toy comprising a pair of wheels, axels secured to said wheels having cranks formed thereon, a frame journaled on said axels, a figure representing an animated object having a body portion, legs pivoted at one end to said body portion and to the axels at their other end, said body portion being placed above the frame, a member supported on said frame adapted to engage the underside of the body portion to change the direction of movement of said body portion imparted to it by said cranks.

35. A toy comprising a pair of longitudinal frame members, axels journaled in said frame members, a bar adjustably connecting said frame members, wheels supported on said axels, a figure mounted on said axels and a vertical upright adjustably positioned in said bar.

40. A toy comprising a frame member, a pair of axels journaled in said frame member having cranks thereon, wheels secured to said axels, a figure in the shape of an animal having a body portion, limbs pivoted at one end to said body and at their other end to said cranks for freely supporting said animal and an upright positioned below the body of said animal for momentarily supporting the same.

45. A toy comprising a frame member, a pair of axels journaled in said frame member having cranks thereon, wheels secured to said axels, a figure in the shape of an animal having a body portion, limbs pivoted at one end to said body and at their other end to said cranks for freely supporting said animal and an upright adjustably positioned to said frame.

50. In testimony whereof I affix my signature.

GEORGE W. FERGUSON.
